UNITED STATES PATENT OFFICE.

CHARLES P. KLEEBAUER, OF COHOES, AND ROBERT M. LACKEY, OF WATERFORD,
NEW YORK.

CARRY BAG.

Application filed June 23, 1921. Serial No. 479,768.

To all whom it may concern:

Be it known that we, CHARLES P. KLEEBAUER and ROBERT M. LACKEY, citizens of the United States, and residents, respectively, 5 of Cohoes, county of Albany, and State of New York, and Waterford, county of Saratoga, and State of New York, have invented certain new and useful Improvements in Carry Bags, of which the following is a 10 full, clear, and exact description.

Among the principal objects which the present invention has in view are: To avoid accidental releasing of the closing flap of a bag of the character mentioned; to 15 strengthen the construction of the closing members of said bag; and to increase the efficiency and desirability of the article mentioned.

Drawings:

20 Figure 1 is a side view of a bag of the character mentioned, constructed and arranged in accordance with the present invention, and shown as in its closed service position.

25 Figure 2 is a similar view, the bag being shown in its open position.

Figure 3 is a detail view, showing the strip of which the reinforcing patches with which the bag is provided are cut.

Description:

The present invention is more particularly an improvement upon the construction of the finger bag envelope for which Patent No. 1,291,024, was granted to Charles P. 35 Kleebeauer, the 14th day of January, 1919. As set forth in the patent referred to, reinforcing material is adhered to coordinated parts of the envelope, said reinforcing members being severed the one from the 40 other at the time of separating the material from which separate and distinct envelopes or bags are formed. While in Figure 3 of the drawings we have shown lines of severance, and the finger holes with which the 45 patch is ultimately provided, it will be understood that when the strip is attached to the material from which the bag is constructed, it is not so severed or punched. The severing of the strip to form the different operating members with which it is 50 provided, and the punching of the hole for the finger of the person carrying the bag are all performed when the strip is adhered to the envelope, the envelope being also severed 55 in conformity therewith.

In Figure 3 of the drawings is shown a series of reinforcing patches 8. The patches 8 when adhered to the web of paper of which the envelope is formed, are severed along the line 9 in correspondence with the 60 shapes of the edges 10 and 11 of the back 12 and flap 13 respectively. It will be understood that when the web is cut the edge 10 of each envelope or bag is at the opposite extremity of that portion of the web 65 forming the bag removed from the edge 11 of the flap. Hence it will be understood that the portion of each patch forming the handle 14 and the clip lug 15 was initially integral with one of the patches having the 70 barbed head 16 and the slit 17 forming a part of another envelope or bag, and different from the patch with which it is in service associated.

As seen best in Figure 2 of the drawings, 75 in their inactive disposition the flaps 13 are preferably outstretched with the handle 14 protected thereby. The clip lug 15 and the barbed head 16 are likewise flush with the parts with which they are associated, and 80 thereby protected against abrasive damage.

When the bags have been filled, the flaps 13 are folded, bending on the line 18, leaving the handle 14 upstanding in its original 85 position. When the handle 14 is thus separated from the body of the bag, an opening is formed therein, bounded by the edge 19. The opening thus formed registers in part with the barbed head 16, while the clip lug 15 registers with the slit 17. The 90 flap 13 and the reinforcing patch associated therewith are bent or bowed to permit the clip lug 15 to enter the slit 17. The slit 17 is disposed as shown best in Figure 1 of the drawings in closer relation to the edge 18 95 than the end of the said clip lug. To admit the lug 15 within the slit 17, the said lug is partly severed from the flap 13 by the side cuts 20. The edges of the cuts 20 associated with the flap 13 form portions 100 of the said flap extending beyond the slit for engaging the material from which the slit is cut to restrain the lug from withdrawal from the said slit.

A further deterrent preventing the withdrawal of the lug from the slit is the barbed head 16. As shown best in Figure 1 of the drawings, the barbed head 16 is drawn through the opening in the flap 13, bounded by the edge 19, and that in this position the 110

lateral extensions of the barbed head 16 overhang or lap the areas of the flap 13 adjacent the said opening therein.

When drawing the head 16 through the opening in the flap 13, the head 16 is engaged by the finger of the operator which partially extends through the finger hole in the handle 14. To assist in this operation the head 16 is so cut as to form a margin 21 that extends above the adjacent edge of the handle 14. The margin 21 resting thus clear of the edge of the finger hole, the said margin is easily engaged when drawing the head through the opening until the barbs of the head spring past the portions of the flap 13 which originally covered them. The resiliency of the material causes the head to then assume the position shown in Figure 1 of the drawings, where it will be noted the lower edge of the barbed head is engaged by the edge 19 of the openings in the flap 13 in line with the lug 15 and slit 17, and in relatively close disposition thereto. From this it is obvious it is difficult or impossible, without marring the envelope, to withdraw the lug 15 from engagement with the slit 17, prior to releasing the flap 13 from engagement by the head 16. The head 16 can be disengaged only by drawing the same outward from the handle 14 until the barbed extensions of the head 16 may be folded upward until they can pass the edge 19 of the opening in the flap. The flap can then be bowed outward, until the lug 15 is withdrawn from the slit 17, thereby releasing the flap to permit it being upturned to the position shown in Figure 2 of the drawings.

It will be understood that while the lug 15 has been shown and described as having straight sides corresponding to the cuts 20, this may be varied indefinitely by shaping the cuts 20 differently. Thus, if desired, the lug 15 may be provided with an enlarged end, the lateral extension of which would hold the lug within the said slit after the manner of the barbed head 16. We have however found the straight-sided lug sufficient for all demands put upon it.

Claims:

50 1. A carry bag having a back and front united to form an end opening receptacle, said front having an extended flap for closing the end of said receptacle; a reinforcing strip permanently attached to said flap to form a stiffened area therein; a handle portion partially severed from said flap and reinforcing strip, to extend from the end edge of said front when said flap is folded in service relation; means for holding said flap in service relation, said means embodying the body of the flap surrounding the opening formed by severing said handle portion, a portion of said back having lateral extensions for engaging

the material surrounding said opening, and a detent on said back engaging said flap in service relation to prevent the separation thereof from contact with said back.

2. A carry bag having a back and front united to form an end opening receptacle, 70 said front having an extended flap for closing the end of said receptacle; a reinforcing strip permanently attached to said flap to form a stiffened area therein; a handle portion partially severed from said flap and reinforcing strip, to extend from the end edge of said front when said flap is folded in service relation; means for holding said flap in service relation, said means embodying the body of the flap surrounding the opening 80 formed by severing said handle portion, a portion of said back having lateral extensions for engaging the material surrounding said opening, and a tongue member formed on said flap at the edge thereof for engaging 85 said back to hold said flap and back in contact.

3. A carry bag having a back and front united to form an end opening receptacle, 90 said front having an extended flap for closing said receptacle; a plurality of co-ordinated reinforcing members attached to said front and to said back, respectively; means for holding said flap in service folded relation to said receptacle, said means embodying a barbed head and opening adapted to have said head passed therethrough, said head and opening being formed in said back and flap, the lateral ends of said head extending beyond the edges of said opening to 100 obstruct the withdrawal of said head from said opening; and means uniting the free edge of said flap and the body of said back when the flap is in folded service relation.

4. A carry bag having a back and front 105 united to form an end opening receptacle, said front having an extended flap for closing said receptacle; a plurality of co-ordinated reinforcing members attached to said front and to said back, respectively; means 110 for holding said flap in service folded relation to said receptacle, said means embodying a barbed head and opening adapted to have said head passed therethrough, said head and opening being formed in said back 115 and flap, the lateral ends of said head extending beyond the edges of said opening to obstruct the withdrawal of said head from said opening; and means uniting the free edge of said flap and the body of said back 120 when the flap is in folded service relation, said means embodying a tongue formed at the edge of said flap, and a slit formed in said back, said tongue being adapted for extension through said slit to be held thereby. 125
